LUBRICANT DISPENSING CABINET WITH
ELEVATORS FOR PLURALITY OF PUMPS
AND VERTICALLY SLIDING FRONT
PANEL

Alexander P. Fox, University City, and August D. Reisert, St. Louis, Mo., assignors to Lincoln Engineering Company, St. Louis, Mo., a corporation of Missouri

Application June 26, 1948, Serial No. 35,498

8 Claims. (Cl. 222—135)

1

This invention relates to lubricant dispensers, and with regard to certain more specific features, to a cabinet type of dispenser operating in connection with commercial lubricant drums.

Among the several objects of the invention may be noted the provision of a safe and convenient lubricant dispenser construction comprising a cabinet for enclosing automatic lubricator pumps and commercial lubricant containers from which the pumps draw their lubricant supply for delivery to distribution lines with or without metering of the lubricant; the provision of a construction of the class described in which the so-called lance-type pumps which are employed can conveniently be placed in elevated positions for removal of empty containers and for replacement by full ones; and the provision of apparatus of this class which may conveniently be opened for reloading and which when closed presents a neat and compact appearance. Other objects will be in part apparent and in part pointed out hereinafter.

The invention accordingly comprises the elements and combination of elements, features of construction, and arrangements of parts which will be exemplified in the structures hereinafter described, and the scope of the application of which will be indicated in the following claims.

In the accompanying drawings, in which one of various possible embodiments of the invention is illustrated:

Fig. 1 is a perspective view of the apparatus in open position, ready for exchange of filled for empty lubricant container drums;

Fig. 2 is a perspective view showing the apparatus in closed position;

Fig. 3 is a vertical, longitudinal section through the apparatus, parts being shown in elevation, and the containers being shown in dotted lines;

Fig. 4 is a cross section taken substantially on line 4—4 of Fig. 3 and showing a door in initial partially open position;

Fig. 5 is an enlarged detail section of upper portions of Fig. 4;

Fig. 6 is an enlarged detail section taken on lines 6—6 of Fig. 3;

Fig. 7 is an enlarged detail cross section taken on line 7—7 of Fig. 3;

Fig. 8 is a vertical section through the partially open door of Fig. 4, being viewed from line 8—8 of Fig. 9 but being on a smaller scale than the latter figure;

Fig. 9 is an enlarged horizontal section taken on line 9—9 of Fig. 8;

2

Fig. 10 is a perspective view of certain container cover parts; and,

Fig. 11 is a diagrammatic hydraulic circuit layout.

Similar reference characters indicate corresponding parts throughout the several views of the drawings.

The so-called lance type of lubricant pump consists of an elongate pump cylinder in which 10 is a reciprocating piston operated by a motive unit carried on the upper end of the cylinder. The intake is at the bottom end of the pump cylinder and the outlet at its top. The motive unit may be an electric motor or an air engine. 15 The device is for insertion into a commercial or like lubricant container from which lubricant is to be pumped. The apparatus may be inserted into the container through its open top or a hole at the top. Typical examples are shown in the 20 following United States patents: 1,925,832; 2,122,020; 2,187,684; 2,215,852; 2,269,423; 2,298,920; and others. These form a desirable class of pump, but it is difficult to make a replacement of a full container for an empty one, particularly when the pump is to be stored, along with its container, in a cabinet, and more particularly when several pumps and several containers are so to be stored. A difficulty that arises is the handling of the pump while container exchange is being made. This is particularly true when the pump is to be organized with a metering system. By means of the present invention, a convenient cabinet arrangement is provided for containing several pumps and several containers in a cabinet with provision for convenient means for holding the pumps in suitable positions when container exchanges are to be made. Furthermore, the pumps are left in association with a hydraulic dispensing and metering system that forms part of the cabinet thus avoiding troublesome connecting and disconnecting problems. In addition, the cabinet parts are arranged for maximum convenience and safety in opening and closing the same while container exchanges are made.

Referring now more particularly to Figs. 1—4, there is shown at numeral 1 in general a covering cabinet which, when closed, presents an attractive appearance (Fig. 2). This cabinet has end walls 3, a rear wall 5 and a front wall 7 in which is an opening 9 (Figs. 1 and 4). Surmounting the walls 3, 5 and 7 is a frame 11. The parts 7 and 11 are notched, as shown at 2 and 4, for the reception of a flow meter panel 6, the latter being attached to the member 7. 55 This panel carries two flow meters 10 and 12.

The frame 11 has a rectangular top opening 13 on the rear edge of which are endwise hinges 15 for a cover 17. The bottom of the cabinet is formed by supporting channel bars 19. These support lubricant containers shown at C, a three-container size being illustrated. At two points between the container locations are carried cross-bars 21. These carry pivots 23 for the lower heads 24 of pneumatic elevator cylinders 27. Air inlets are shown at 29 with which are connected air leads 31. These leads are sufficiently flexible to permit limited pivotal movement of the cylinders. They may be of copper tubing, if desired. The cylinders pass loosely through guide openings 33 of a rigid bridge member 25. The bridge member extends lengthwise within the cabinet, being supported at its ends 35 on vertical columns 37 which form part of the structural skeleton for the enclosing walls. The elevation of the bridge 25 above the supports 19 is sufficient for lateral acceptance through opening 9 of the containers C.

Within the cylinders 27 are pistons 39 having piston rods 41 slidable through the closed upper ends 43 of the cylinders. Outside, the rods 41 are attached to a crosshead 45, which extends a substantial distance throughout the length of the cabinet. The rod connections for this purpose are shown at 47. Supported on the crosshead 45 by other connections 49 are pneumatic engines 51 with which are organized in the usual way depending lance-pump cylinders 53. These cylinders pass through suitable openings 55 in the bridge 25. By introducing air into the cylinders 27 through lines 31, the pistons 39 are raised, thus raising the crosshead 45. This lifts the engines 51 and pump cylinders 53. The action is limited by stop cylinders 57, carried around the piston rods 41 within the cylinders 27, so that the lower ends 59 of the cylinders 53 move to an elevation just above covers 61 for the containers C, but not through the openings 55 in the bridge. A spring bumper 63 is attached centrally to the crosshead 45 for the purpose of automatically pushing open the cover 17 when the pumps are lifted. The cover 17 is never locked down, so that there is no chance of attempting to effect a lift against a closed cover. When the pumps are depressed, the cover is closed by hand and maintains its closed position under gravity.

It will be seen that, if desired, the cover 17 could be carried on and have translation with the crosshead 45. While this is a feasible construction, the construction shown, wherein the cover 17 is hinged to the cabinet, is superior. This is because the hinged cover opens automatically upon elevating the pumps, but is not closed automatically as it would be if the cover were carried on the crosshead 45. The superiority rests in the fact that it becomes impossible for an operator accidentally to have his hand under the cover when it is being automatically closed, as would be the case if the cover were carried on the crosshead. With the construction shown, he manually closes the cover 17 after the parts are in retracted positions. However, in its broader aspects the invention includes any cover which automatically opens in response to pump elevator operation, whether or not the cover is automatically closable.

An advantage of the lift construction specified is that, although the lower ends of the pumps may be lifted clear of the containers in the

cabinet, they are steadied by the bridge 25 in their elevated positions. The elevators, consisting of the parts 27, 39 and 41, are also steadied by the bridge 25, although they are only pivoted at 23 to the supports 21. Thus all the sliding, elevating parts are sufficiently guided without requiring excessive accuracy of guiding and guided parts.

Fig. 10 shows a detail of one of the covers 61, which comprises two semicircular halves 65 carrying slots 67 and cooperating catches 69 with central openings 71. The edges of the parts 65 rest on the upper ends of the containers and the openings 71 accommodate the pump cylinders 53. These covers are removed when an exchange of containers is made.

On the crosshead 45 is carried a manifold pipe 73 which supplies air to the air pumps 51 through flexible hose connections 75 (Fig. 11). This pipe 73 is supplied with air by a flexible hose 77 leading from a rigid pipe 79, part of which is on the bridge 25. Pipe 79 supplies air to the cylinders 27 through said flexible hose connections 31. Pipe 79 is supplied with air from a line 95, regulator 97, gage 98, hose 101 and a coupler 102. Pipe 79 includes hand control valves 81 and 83 on opposite sides of the connection with hose 77. The controls for valves 81 and 83 pass through one end of the frame as shown in Fig. 2, so they may be reached from the outside. By controlling valve 81, air may be supplied or cut off from the entire system. By controlling valve 83, the air supply to the lift cylinders is controlled. It should be noted in this connection that air is only intermittently required for lifting purposes, but it is potentially required at all times for the pumps 51, which are the full-stroke variety. These stop automatically when the lubricant pressure in the pump cylinders 53 builds up to a predetermined point. When this pressure reduces, as by a demand for lubricant at outlet lines 85, 87 or 89, the pumps automatically start. This is clear from said patents.

The outlet line 87 extends to the bottom of the cabinet for connection with a distribution pipe 93 shown in Fig. 11 but not in Fig. 1. The outlet lines 85 and 89 extend to meters 10 and 12, respectively. Lines 14 and 16, respectively, from these meters pass to the bottom of the cabinet. At their lower ends, the lines 14 and 16 are connected to the two other distribution pipes 93 shown in Fig. 11 but not in Fig. 1. The distribution pipes 93 may extend under or over the floor upon which the cabinet rests. The inlet pipe 95 may also extend to the cabinet over- or under-ground. It will be understood that pipes 93 and 95 are not parts of the dispenser per se, but are furnished separately for the installation of the dispenser. The lubricant in lines 85 and 89 may be of the flowing type, which is to be metered, and the lubricant from the line 87 of more viscous type, such as grease, which is not metered. The dials of the meters 10 and 12 may be read from the front of the cabinet.

The opening 9 is covered by a door indicated generally at 103. This door comprises a panel 105 carrying a lift rail 107 and pivoted at lower pivots 109 on brackets 111 located at the lower corners of the opening 9. The pivots are not directly upon the panel 105 per se but are carried upon the lower ends of side bars 113 associated with the panel. The bars 113 are channel-shaped, as shown in Fig. 9. Welded to them are outwardly facing channel portions 115 with-

in which slide portions of an intermediate telescoping bar 117. Other portions of this bar 117 telescopically slide within channels 119, which are welded to the panel 105 proper. Thus the entire door may swing on the lower pivots 109 of the combined telescoping members 113, 115, 117 and 119. If the door 103 is swung out and pulled up, the bars 117 may slide in members 115 and the door channels 119 may slide on the members 117. Thus there is a swinging arrangement of the panel 105 on telescoping side bar constructions which are pivoted at the lower corners of the opening 9.

When the door 103 is shut, thumb nuts 121 carried in the panel 105 may be threadingly engaged with screws 123 carried on the lower edge member 125 of the part 7. This locks shut the panel. When these thumb nuts are disengaged, the door is biased outward a limited amount, as shown in Fig. 8. The limited pivotal opening is brought about by means of the construction shown in Figs. 4 and 9. One construction may be used at each panel side, but only one is described for brevity. Each construction consists of a bracket 127 carried on the frame of the cabinet. Ears 129, having openings therein, accommodate a keyed guide pin 131 upon which rides a slide member 133 to which is bolted a member 135. The latter is attached to the upper end of one of the channel bars 113. A spring 137 biases the parts 133, 135 and the upper ends of 113 to push the panel outward when unlocked, at 121, 123. As indicated, the biasing construction may be duplicated on each side of the opening 9 in connection with each pivotal bar 113.

In order to open the panel, as shown in Fig. 1, it is provided at the bottom with interior brackets 139 in which are sliding pins 141 biased by springs 143 toward the channels 113. Openings 145 (Fig. 8) toward the upper ends of the channels 113 accept the biased pin 141 in an elevated position of the panel 105. Thus the panel may be lifted and held in raised position. Only one holding structure is shown (Fig. 9) since the other one on the opposite side is a duplicate.

Short levers 147 located on the lower edges of the door and pivoted at 149 cooperate with keys 151 on the pins 141 to retract them from the openings 145. When the door is up, these levers 147 can be reached for manipulation to retract the pins. Then the door may be allowed to gravitate downward, as the bars 115, 117 and 119 telescope together. Then the door may be pushed in from the Fig. 8 position to the Fig. 2 position, the thumb nuts 121 being applied to the screws 123 for permanent closure.

The door construction described has the advantage that there is never any necessity for swinging the panel over a large sweep area. With the door construction used, the telescoping channels act as pivoted vertical guides so that the door panel may be either placed in closed position or angled forward slightly, the latter preparatory to lifting the panel. When the panel is lifted, it takes up head room only of the amount required in any event for the elevator crosshead 45. In addition, the trajectory of the panel is clear of the protuberances associated with the meter panel 6 (note Figs. 2 and 4).

In view of the above, it will be seen that the several objects of the invention are achieved and other advantageous results attained.

As many changes could be made in the above

constructions without departing from the scope of the invention, it is intended that all matter contained in the above description or shown in the accompanying drawings shall be interpreted as illustrative and not in a limiting sense.

We claim:

1. Lubrication apparatus comprising an enclosing cabinet having a rectangular vertical access opening, a substantially vertical panel for closing said opening, said panel comprising telescoping upwardly extending side bars pivoted at their lower ends to the lower corners of said opening, an element limiting opening movement of the upper end of the panel to an angled partially open position, the panel being slidable up and down by means of said telescoping side bars, and releasable lock elements between the panel and bars whereby the former may be locked completely open in an upper position relative to the side bars or dropped to said partially open angled position.

2. Apparatus made according to claim 1 including a lock element operative between the panel and the cabinet for holding the panel shut when swung in toward the cabinet from said angled position.

3. Lubrication apparatus comprising an enclosing cabinet having a rectangular vertical access opening, an essentially vertical panel for closing said opening, said panel comprising telescoping upwardly extending side bars pivoted at their lower ends to the lower corners of said opening, an element limitedly biasing forward the top of the panel, a first releasable locking element for holding the panel shut against the bias, the panel being slidable by means of said telescoping side bars, and a second releasable lock element operable from the panel whereby the latter may be locked in an upper position relative to the side bars or dropped to its biased position.

4. Apparatus made according to claim 3 in which said first locking element is operative from the top of the panel and the second locking element is operative from its bottom.

5. A lubricant dispenser comprising a cabinet having a vertical front opening and a horizontal top opening, a bottom support for the reception of exchangeable lubricant containers adapted to be spaced from one another in the cabinet, an interior bridge construction above said containers, cylinder elevators pivoted to said bottom support between the containers and having portions passing loosely through said bridge but being steadied thereby, a crosshead carried by the elevators, lance pumps depending from the crosshead and passing movably through the bridge into and out of the containers, a cover for said horizontal opening which is openable by a part of the crosshead upon elevation to lift the pumps from the cabinet when their lower ends are retracted from the containers, a closure panel for said front opening including upwardly extending telescoping side bars pivoted to the lower corners of the vertical opening, and mechanism determining limited swinging opening movement of said panel on said pivots, whereby the panel may be moved upward by telescoping movement of said bars to clear the panel from the front opening for the removal and reception of the containers.

6. A lubricant dispenser comprising an enclosing cabinet having a front opening for the reception of at least one lubricant container within the cabinet, and having a top opening, an elevator in the cabinet including a lifting element from

which a pump is suspended for insertion into and retraction from said container, a cover for said top opening engaged by a part of said lift element automatically to be opened when the pump is lifted from the container, the pump being moved through said top opening when elevated to clear the container for replacement of the latter, an openable panel for said front opening, said panel comprising telescoping upwardly extending side bars pivoted at their lower ends to the lower corners of said front opening of the cabinet, an element limitedly biasing forward the top of the panel, and locking elements for holding the panel shut against the bias when desired, the panel being movable up and down by means of said telescoping side bars.

7. A lubricant dispenser comprising an enclosing cabinet having a front opening for the reception of at least one lubricant container within the cabinet, and having a top opening, an elevator in the cabinet including a lifting element from which a pump is suspended for insertion into and retraction from said container, a cover for said top opening engaged by a part of said lift element automatically to be opened when the pump is lifted from the container, the pump being moved through said top opening when elevated to clear the container for replacement of the latter, an openable panel for said front opening, said panel comprising telescoping upwardly extending side bars pivoted at their lower ends to the lower corners of said front opening of the cabinet, an element limitedly biasing forward the top of the panel, locking elements for holding the panel shut against the bias when desired, the panel being movable up and down by means of said telescoping side bars, and releasable lock elements operable from the lower edge of the panel whereby the panel may be locked in an upper position relative to the side bars or dropped to a closing position.

8. Lubricant dispensing apparatus comprising an enclosing cabinet having a front opening and a bottom support for the interchangeable reception of spaced lubricant containers, a bridge construction within the cabinet above the containers, air lifts fastened to the bottom support and extending through said bridge, an upper crosshead carried by said lifts, lance pumps suspended from said crosshead and extending downward through said bridge, said cabinet having an upper opening, said crosshead and suspended pumps being vertically movable through said top opening by means of said lifts, the lower ends of said pumps being movable from lower positions in the containers to elevated positions clear of the containers but not above the bridge, pivots for the elevators at their lower ends to the bottom support, and vertically movable piston-operated rods in the cylinders, said cylinders being located between the containers, and said pumps alternating in positions respective to the lifts and being substantially centered with respect to the containers.
